[57] CLAIM

The ornamental design for a combined electrical terminal casing and integral fastening lug thereof, as shown and described.

DESCRIPTION

FIG. 1 is a rear perspective view of a combined electrical terminal casing and integral lug showing minute design.

FIG. 2 is a front view thereof on a reduced scale.

FIG. 3 is a side view thereof on a reduced scale, the opposite side being identical.

FIG. 4 is a top view thereof on a reduced scale.

FIG. 5 is a bottom view thereof on a reduced scale.
